United States Patent Office

Des. 232,010
Patented July 9, 1974

232,010

MUG

Dieter Steinmann, Glendale, N.Y., assignor to European Design Corporation, Glendale, N.Y.

Filed Nov. 20, 1972, Ser. No. 308,219

Term of patent 14 years

Int. Cl. D7—01

U.S. Cl. D7—9

FIG. 1

FIG. 2

FIG. 3

FIG. 5

FIG. 4

FIG. 6

FIG. 1 is a top isometric view of a mug showing my new design;

FIG. 2 is a bottom isometric view thereof;

FIG. 3 is a side elevation view thereof;

FIG. 4 is a front elevation view thereof;

FIG. 5 is a rear elevation view thereof; and

FIG. 6 is a top plan view thereof.

The side of the mug opposite the side shown in FIG. 3 is a mirror image thereof.

I claim:

The ornamental design for a mug, substantially as shown and described.
